UNITED STATES PATENT OFFICE

CHARLES W. H'DOUBLER, OF RACINE, WISCONSIN

MOTOR-GEARED SEWING MACHINE

Application filed July 2, 1925. Serial No. 41,096.

This invention relates to improvements in motor geared sewing machines.

It is one of the objects of the present invention to provide a motor geared sewing machine in which the motor and driving mechanism is positioned within the arm of the sewing machine.

A further object of the invention is to provide a motor geared sewing machine in which the driving connection may be easily connected to and disconnected from the sewing machine shaft in a very simple manner and exteriorly of the arm of the sewing machine.

A further object of the invention is to provide a motor geared sewing machine in which the armature of the motor is journaled entirely in the arm of the sewing machine.

A further object of the invention is to provide a motor geared sewing machine in which the sewing machine shaft is provided with a squared portion for connecting the clutch member thereto.

A further object of the invention is to provide a motor driven sewing machine having a friction driven bobbin-winder which may be rotated during the operation of the machine or while the sewing machine is disconnected.

A further object of the invention is to provide a motor geared sewing machine which is very compact, is strong and durable, and inexpensive to manufacture, and is well adapted for the purpose described.

With the above and other objects in view, the invention consists of the improved motor geared sewing machine and its parts and combinations as set forth in the claims, and all equivalents thereof.

In the accompanying drawing in which the same reference characters indicate the same parts in all of the views:

Fig. 1 is a side view, partly taken on section line 1—1 of Fig. 2, of a portion of the standard and arm of a sewing machine enclosing the motor and gearing;

Fig. 2 is a rear view thereof with the hand wheel removed;

Fig. 3 is a vertical sectional detail view showing a portion of the cranked shaft and parts connected thereto; and

Fig. 4 is a sectional detail view of the clutch mechanism.

Referring to the drawing, the numeral 8 indicates a tubular standard of a sewing machine, and 9 a tubular arm communicating with the standard and projecting therefrom, said parts forming the head of the machine. The upper portion of the standard is formed with a side extension 10 to provide space for receiving an electric motor 11 mounted therein. The rear portion of the extension and the corresponding portion of the standard in horizontal alinement therewith are opened and closed by a cap or cover 12 which is secured in position by screws 13. Said cap is recessed into the parts, as at 12', to hold the parts in alinement. The armature shaft 14 of the motor is journaled in the extension 10 and in the cap 12, and the motor is maintained in position by screws 15 which thread into portions of the extension. The extension and cap are also provided with oil cups 16 for lubricating the armature shaft 14. The cap 12 is formed on its inner side with a gear compartment 17 closed by an inner cover 18 secured to the outer cap by screws 19. A train of gears 20, 21, 22, 23 and 24 are positioned within the compartment, and are intermeshed to transmit motion from the armature shaft 14 to the cranked sewing machine drive shaft 25, and also to the bobbin-winder friction wheel 26 which projects outwardly a slight distance through an elongated opening 27 formed in a side portion of the cap 12. The gear 20 is loosely journaled on the sewing machine shaft 25 and the gear or pinion 23 is mounted fast on the armature shaft 14 while the gears 21 and 22 are connected together and are mounted on the short shaft 28 journaled in the cap 12. The friction wheel 26 and the gear 24 are also connected together and are also mounted on a short shaft 29 which is journaled in the cap 12. The armature shaft 14 is also provided with a beveled edge wheel 30 in which the portion 30' of larger diameter extends into the compartment 17 to prevent oil from the gears working towards the armature of the motor.

As arranged, the oil from the compartment will work to the portion of the wheel of larger diameter and be thrown

off therefrom by centrifugal force in the compartment and against the gears therein. Commutator brushes 11' are also mounted in the side extension 10.

5 The gear 20 is mounted on and forms part of a jawed clutch member 31 which is journaled on the cranked sewing machine shaft 25 between the cap bearing 12' and shoulders 32 formed by a squared or rectangular portion 33 of the shaft 25. Said squared portion has slidably mounted thereon a jawed clutch member 34 complementary to the clutch member 31 and which member 34 may be moved into clutching engagement with the member 31 to lock the gear 20 to the shaft 25 when it is desired to run the machine. The member 34 is formed with a squared bore 34' to fit the squared shaft portion 33 and turn therewith. The clutch member 34 is also formed with an 20 annular groove 35 to receive a semicircular shoe 36 positioned therein. A medial portion of the shoe is formed with an outward projection 36' which extends through a rectangular opening 37 in the operating lever 38. Said lever is pivotally connected at its lower 25 end to the cover 18 of the cap 12 as indicated by the numeral 39 while the upper end extends through an elongated opening 40 in the upper portion of the sewing machine arm 9 as clearly indicated in Fig. 1.

An arm 41 pivotally and frictionally connected to the standard 8 by a pivot bolt 42 has journaled in its upper end a bobbin shaft 43 for receiving ordinary bobbins (not 35 shown), and said shaft has mounted fast thereon a rubber banded friction wheel 44 which frictionally engages the wheel 26 and is rotated thereby when the arm 41 is swung upwardly.

40 A hand wheel 45 is mounted on the outer end of the cranked shaft for turning or stopping the shaft manually. As thus constructed the entire rotary parts of the machine can be disconnected from the motor and remain at rest while the motor is running and 45 the bobbin winder can be rotated through the gears whether or not the sewing machine elements are in operation.

From the foregoing description it will be 50 seen that the motor is mounted entirely in the arm of the machine but can be easily removed by taking off the end cap. Furthermore the end cap compartment also provides for the easy removal of all of the gears as a unit in 55 a very simple manner, and the location of the gears and the motor do not interfere with the other portions of the sewing machine. The squared portion of the sewing machine shaft eliminates the use of keys or screws and 60 provides a simple connection for the clutch member.

What I claim as my invention is:

1. A motor geared sewing machine, comprising a tubular sewing machine head having a rear open end portion, a cap closing

said end, a horizontal drive shaft journaled in the head and the cap, and having a rectangular portion, a clutch member slidably, but non-rotatably mounted on the shaft, a gear wheel journaled on the shaft and having a 70 complementary clutch portion engageable by the clutch member to lock the gear to the shaft, means for moving said clutch member into and out of engagement with the clutch portion, an electric motor journaled entirely 75 in the head and the cap and having its shaft parallel to the drive shaft, and a train of gears connecting the motor shaft to the gear wheel on the horizontal drive shaft.

2. A motor geared sewing machine, comprising a tubular sewing machine head having a rear open end portion, a cap closing said end and having an inner compartment, a horizontal drive shaft journaled in the head and cap and extending through the compartment, a clutch member slidably but non-rotatably mounted on the drive shaft, a gear wheel positioned in the compartment and journaled on the drive shaft and having a complementary clutch portion engageable by the clutch member to lock the gear to the shaft, means for moving said clutch member into and out of engagement with the clutch portion, an electric motor entirely within the head and having its shaft parallel to the drive 85 shaft and journaled in the head and extending through the compartment and journaled in the cap, and a train of gears within the cap compartment and connecting the motor shaft to the gear wheel on the drive shaft. 90

In testimony whereof, I affix my signature.

CHARLES W. H'DOUBLER.
